UNITED STATES PATENT OFFICE.

GARY B. SMITH, OF CHICAGO, ILLINOIS; HATTIE C. SMITH ADMINISTRATRIX OF SAID GARY B. SMITH, DECEASED.

CHAIN AND CROSSTIE LINK ASSEMBLING MACHINE.

Application filed May 9, 1923. Serial No. 637,785.

To all whom it may concern:

Be it known that I, GARY B. SMITH, a citizen of United States, residing at Chicago, in the county of Cook and State of

5 Illinois, have invented certain new and useful Improvements in a Chain and Crosstie Link Assembling Machine, of which the following is a specification, reference being had therein to the accompanying drawing.

10 The present invention is a machine for applying cross tie links to a chain or other member from which bed fabrics and the like are made, and it is the primary object of 15 the invention to provide a novel and improved machine of that kind, which will operate in a practical and efficient manner.

As a further object, the invention aims to 20 provide such a machine which is improved generally in its construction and details, to enhance the utility and efficiency thereof.

Another object is the provision of means 25 for bending portions of the cross tie links into hooks embracing the chain or other articulated member and for closing said hooks on such member to securely fasten the cross tie links thereto one at a time in succession at longitudinally spaced points of said chain or member.

30 A further object is to provide such a machine which will bend the loops of doubled wire cross tie links into hooks around the chain or similar member.

With the foregoing and other objects in 35 view, which will be apparent as the description proceeds, the invention resides in the construction and arrangement of parts, as hereinafter described and claimed, it being understood that changes can be made within 40 the scope of what is claimed, without departing from the spirit of the invention.

The invention is illustrated in the accompanying drawings, wherein—

Fig. 1 is a plan view of the machine.

45 Fig. 2 is an elevation thereof.

Fig. 3 is an enlarged vertical section on the line 3—3 of Fig. 1.

Fig. 4 is an enlarged detail plan view of the bending devices and corresponding parts, portions being shown in section.

Fig. 5 is an enlarged detail elevation of the cross tie link applying and forming devices.

50 Fig. 6 is a horizontal section on the line 6—6 of Fig. 5.

Fig. 7 is an elevation, corresponding with Fig. 5, showing a modification.

Fig. 8 is a horizontal section on the line 8—8 of Fig. 7.

55 Figs. 9 and 10 are sectional details on the respective lines 9—9 and 10—10 of Fig. 8.

Fig. 11 is a detail elevation of the loop bender at the start of its movement through the loop of the cross tie link.

60 Fig. 12 is a similar view showing the loop bender in position to start the bending of the loop.

The present machine employs in combination the chain making mechanism or sub-machine A, substantially the same as disclosed in my Patent No. 1,153,266, granted 70 September 14, 1915, and the cross tie link making mechanism or sub-machine B, which is substantially the same, in general respects, as disclosed in my Patent No. 1,116, 75 506, granted November 10, 1914, such mechanisms being co-related and an organization effected for applying the cross tie links to the links of the chain. Such mechanisms are substantially the same as disclosed in 80 said patents, with the changes and improvements as hereinafter described. The mechanism B has a drive shaft 20 driven by the sprocket chain 21 or other means for operating the cross tie link making mechanism, 85 and the chain making mechanism A has the drive shaft 20 which is driven from the drive shaft 20 of the cross tie link making mechanism by means of the shaft 23 geared to the shaft 22 and connected by the sprocket 90 chain 24 with the shaft 20, although other gearing can be used for driving the chain making mechanism from the cross tie link mechanism.

95 The chain making mechanism A produces, substantially the same as disclosed in Patent No. 1,153,266, a chain composed of the doubled wire links 25, each having a loop 26 at its forward end and hooks 27 at its rear end formed by doubling the terminals 100 of the wire back, the loops and hooks of the links being interengaged, and the links having the separated or offset portions 28 adjacent to the loops for the application of the cross tie links to the chain links 25 between 105 the loops 26 and offsets 28. The mechanism A forms the chain links as the mechanism B forms the cross tie links, the operation of the mechanism A being substantially the same as disclosed in Patent No. 1,153,266. 110

The cross tie link mechanism B has a reciprocating feeder or advancer 30 for intermittently feeding or advancing the wire 31 from which the cross tie links are fashioned, 5 and said mechanism has the bending device 32 for bending the forward terminal portion of the wire 25 back, substantially the same as disclosed in Patent No. 1,116,506, and after the wire is thus bent it is fed or advanced forward by the feeder or advancer 30 over a hook bending member 33 and a loop bending and anvil member 36. The cross tie link 34 of doubled wire is of loop form, and the terminals and loop of the wire 10 are bent back into the respective hooks 35 and 35' at the opposite ends of the link, and with the present machine, the loop hook 35' of the cross tie link is made to embrace the chain link 25 between the loop 26 and offsets 15 28, thereby producing a chain having the cross tie links attached at their looped ends. The production of the cross tie links, generally considered, by the mechanism B is substantially the same as disclosed in Patent 20 No. 1,116,506, but in using the patented mechanisms in combination for applying the cross tie links to the chain, provisions are made to accomplish the desired results.

The cross tie link mechanism includes a 25 tubular rock shaft 37 journaled in the frame 42 and carrying the hook bending member 33 at that end opposite to the mechanism A, and the loop bending member 36 is carried by the corresponding end of a tubular shaft 38 journaled in the frame parallel with the shaft 37. The shafts 37 and 38 have the gear wheels 39 and 40 thereon, respectively, meshing with one another, so that said shafts turn simultaneously in opposite directions, 40 the gear wheels being of such diameter that the shafts are turned through substantially the same angle for bending the hooks 35 and 35'. The mechanism B has a rack 41 reciprocated from the drive shaft 20 and meshing 45 with the gear wheel 39 for oscillating the shafts 37 and 38 in proper timed relation, and the wire feeder or advancer 30 is also reciprocated from the shaft 20.

In using the mechanisms A and B in combination for applying the cross tie links to the chain, a guide tube 43 is fitted within the tubular rock shaft 38 and extends from the member 36 beyond the opposite end of the shaft 37 and is secured to the frame 42 beyond said shaft, so that the guide 43 remains stationary, while the shaft 38 rotates around said tubular guide. The guide 43 serves to guide the chain therethrough to pass through the shaft 38 and over the member 55 36, and the guide 43 has a longitudinal slot 44 in the top thereof in which the hooks 27 of the chain links 25 move, in order to guide the chain links and hold said links against turning motion. A bar 45 of substantially

semi-circular section is fitted in the tubular 65 guide 43 at the bottom thereof, with its flat surface uppermost, so that the chain links slide over the bar in moving through the guide 43. That end of the bar 45 adjacent to the member 36 has a reduced extension or tongue 46 to project out over the member 36 and to provide a substantial element around which the hooks 35' of the cross tie links can be bent, as will hereinafter 70 more fully appear. A screw 47 is secured in the bar 45 near the tongue 46 and works in a longitudinal slot 48 in the bottom of the guide 43 to prevent angular or transverse displacement of the bar 45 and its extension 75 46, and a second screw 49 is engaged in the bar 45 near the opposite end thereof and depends through a longitudinal slot 50 in the guide 43. The screw or member 49 engages a reciprocating cross head 51 which is 80 slideable on the guide 43, and the cross head 51 is reciprocated in proper timed relation by a lever 52 of the mechanism B which is oscillated from the drive shaft 20.

A rod 53 is slideable through the shaft 37 90 to project out over the member 33, and projects from the opposite end of the shaft 37 through the cross head 51, and said rod is secured to the cross head by means of a set screw 54. The rod 53 and bar 45 are reciprocated as a unit to be projected over and retracted from the bending members 33 and 36, respectively.

A die 55 is mounted for vertical movement 100 above the bending and anvil member 36, being slotted to engage the pins 56 and 57 carried by the frame, and a lever 58 is fulcrumed on the pin 56 and is connected by a link 59 with the die 55 for reciprocating said die. A bar 60 is connected to the upper long 105 arm of the lever 58 and extends past the feeder or advancer 30. Said bar is moved forwardly by a spring 61, so as to swing the lever 58 to the position as shown in Fig. 5, thereby pulling the link 59 upwardly and raising the die 55. The bar 60 carries a pin 62 projecting behind the feeder 30, so that when said feeder is moved to its rearmost position, the feeder contacts with the pin 62, thereby moving the bar 60 rearwardly and 110 swinging the lever 58 toward a vertical position, thereby shoving the link 59 downwardly, said link and lever providing a toggle connection, whereby to force the die 55 down with considerable pressure in its lowermost position, the lower end of the die being formed to close and shape the hook 35' of the cross tie link on the chain.

The guide tube 43 extends rearwardly to the mechanism A to receive the chain from 115 said mechanism, and a supplementary bar 45' is disposed in the guide 43 in rear of the bar 45 to support the chain for movement in the guide 43. The chain links thus pass

from the mechanism A into the guide 43, and are fed from the mechanism A through the guide 43.

The chain is fed or advanced through the 5 guide 43 step by step in synchronism with the feeding or advancing of the wire 31. Thus, a slide 70 is mounted for reciprocation in the frame 42 and frame of the mechanism A, and a pivoted hook or dog 75 is 10 carried by the slide 70 and works in the slot 44 of the guide 43, whereby the reciprocation of the slide 70 will advance the chain link after link, to push the chain past the cross tie link applying means.

15 The slide 70 is operated simultaneously with the wire feeder 30 from the mechanism B, so that the chain and cross tie wire are both advanced at the same time. Thus, the slide 70 is connected by a link 75 with a bell 20 crank lever 77 fulcrumed on the frame 42, and said lever is connected by a link 78 with the feeder 30. Therefore, when the feeder 30 is advanced, the link 78 swings the lever 77 so that the link 76 is pulled forwardly to advance the slide 70, and the hook 75 in engaging the rear end of the corresponding chain link, will slide the chain forwardly, thereby pulling the last chain link from the mechanism A. The chain feeder 25 thus pushes the chain past the cross tie link applying means, and pulls the chain links from the mechanism A as the chain links are formed. The hook 75, when moved rearwardly, passes over the chain links and drops behind the rear end of the corresponding link, as seen in Fig. 3. When the feeder 30 returns, the slide 70 is moved rearwardly. The joint 79 between the link 76 and lever 77 is preferably adjustable so as to regulate 30 the amount of movement of the slide 70 and hook 75, according to the length of the chain links.

The operation of the machine is as follows: When the feeder 30 of the mechanism B advances the wire 31 over the member 33 and onto the member 36, to bring the bend or loop of the wire on the member 36, the slide 70 is also advanced to feed the chain through the guide 43 and over the member 33, the doubled wire 31 passing under the chain. While the mechanism A is advancing the chain the length of one chain link through the tubular guide 43 over the bars 45' and 45, the feeder 30 of the mechanism B advances the double wire 31. The cross head 51 is then moved forwardly so as to project the tongue or extension 46 of the bar 45 and the forward end of the rod 53 over the members 36 and 33, respectively, so that the double wire 31 is disposed below the tongue 46 and rod 53, and when the chain has been advanced the length of one link, a link of the chain is so arranged that the portion thereof be-

tween the loop 26 and offsets 28 is disposed 65 on the tongue 46 of the bar 45 with said tongue in projected position. The rack 41 is now moved to turn the shafts 37 and 38, and the members 33 and 36 are turned clockwise and counter clock-wise respectively as 70 seen in Fig. 5. The member 33 bends the terminals of the cross tie link wire, after cutting the wire 31 between the cutting edge 100 of the member 33 and a cutting edge 101 on the frame under which the wire 31 75 passes, thereby severing the cross tie link from the wire. The turning movement of the member 33 will bend the terminals of the wire constituting the cross tie link, such terminals being bent upwardly over and 80 around the projected rod 53, to form the hooks 35 at one end of the cross tie link. The member 36 being turned will bend the loop of the link upwardly and around the tongue 46 and chain link between the loop 85 26 and offsets 28 of the chain link. The tongue 46 provides a rigid portion around which the wire can be bent by the member 36 without distorting or displacing the chain link during the bending of the loop 90 into the hook 35'. The bending member 33 has bevelled lugs 102 adjacent to the cutting edge 70 and said lugs having converging faces to force and hold the terminals or hooks 35 of the wire together between the 95 lugs when bending them into hooks. The member 36 has a stop 104 on the face thereof against which the loop or bend of the link 34 abuts when the wire 31 is advanced. The rack 41 is then retracted, so as to turn 100 the shafts 37 and 38 and members 33 and 36 to normal position, and the cross head 51 is returned to withdraw the bar 45 and rod 53 from over the bending members. Then, when the feeder 30 returns to its rear-most position it strikes the pin 62, thereby 105 moving the rod 60 rearwardly slightly, and swinging the lever 58 to force the die 55 down. This will close the hook 35' of the cross tie link 34 on the chain link, the member 36 serving as an anvil while the hook 35 is being crushed down around the chain link against said member 33, the tongue or extension 46 having been withdrawn from the hook 35' so that it can be closed around 110 the chain link. When the feeder 30 starts forward to advance the wire 31 to produce the next cross tie link, the rod 60 is moved forwardly by the spring 61, thereby raising the die 55, and the chain being advanced one 115 step will carry the cross tie link with it off of the members 33 and 36. The operation is then repeated as before, so as to apply a cross tie link to each link of the chain.

The chain thus made with the cross tie links thereon can then be fabricated, sections of the chain being disposed parallel

with one another, with the hooks 35 engaged around the chain links within the loop hooks 35' of the companion cross tie links.

Figs. 7 to 12, inclusively, show a modification of the loop bending means. The bar 45" within the tubular guide 43 does not reciprocate, and has a channel or slot 46' therein to permit the hooked ends of the chain links to move in said channel or slot, 10 while the loops 26 and offsets 28 slide on the bar 45" at the opposite sides of the channel. The frame 42 has secured thereto a block or bracket 107 having a surface 108 on which the link 34 rests while being formed 15 and applied to the chain. The block 107 has the channel or slot 109 in alinement with the channel 46' for the passage of the hooked ends of the chain links, and said block has an abutment 110 and an undercut abutment 111 at opposite sides of the channel 109, whereby the loop 26 of the chain link which is in position to receive the cross tie link thereon bears at opposite sides against the abutments 110 and 111, thereby preventing 25 the chain link from being displaced transversely, and the chain link engaging under the undercut abutment 111 will prevent the chain link from turning with the bending member. The block 107 has an inclined surface 112 leading to the abutment 110, so that the cross tie link can ride over said inclined surface and abutment when carried forwardly with the chain after the cross tie link is fastened to the chain.

30 The loop bending member 36' is secured to the forward end of the shaft 38, and has a curved finger 105 which is normally in the position as seen in Fig. 11, whereby the loop of the link moves over the end of the finger, when the cross tie link wire is advanced to link applying position. The bending member 36' has a notched loop seat 106 at the basal end of the finger 105 to engage the loop and bend it around the chain.

35 In operation, the rod 53 and bending member 33 operate the same as hereinbefore described, and when the member 33 bends the terminals of the cross tie link wire around the rod 53, the bending member 36' is rotated in the same direction as but further than the bending member 36. The finger 105 moves upwardly through the loop of the cross tie link and over the chain link 25, as seen in Fig. 12, and the seat 106 contacts 40 with the loop and bends the loop upwardly, over and around the chain link 25, as seen in Fig. 7, thereby bending the loop hook 35' and closing it around the chain link with one operation. The chain link engaging the abutments 110 and 111 will be retained in 45 position while the hook 35' is being bent around the chain link, and when the rod 53 and member 33 are returned to normal position, the bending member 36' is also returned, so that the cross tie link can move

with the chain, said link moving over the inclined surface 112 to pass the abutment 110.

Having thus described the invention, what is claimed as new is:—

1. A machine of the character described including a bending member having a finger to pass through the loop of a doubled wire link around a chain or other member and a portion to bend the loop around said chain or member after the finger has moved through the loop. 75

2. A machine of the character described including a rotary bending member having a curved finger to pass through the loop of a doubled wire link and around a chain or other member, and having a seat to contact with said loop after the finger has passed through said loop, for bending the loop around said chain or member. 80

3. A machine of the character described comprising means for advancing a chain or other member, means for supplying a doubled wire link, and bending means including a finger movable through the loop of said link around said chain or member, and having a portion to contact with the loop and bend the loop around said chain or member. 90

4. A machine of the character described comprising means for advancing a chain or other member, means for supplying a doubled wire link, and a rotary bending member having a curved finger to pass through said loop and around said chain or member, and having a seat to contact with said loop after the finger has moved through the loop, for bending the loop around said chain or member. 100

5. A machine of the character described comprising means for advancing a chain, a guide through which the chain is advanced, means for bending a link around said chain beyond said guide, and a support for said chain beyond said bending means having abutments for the engagement of the chain links to prevent the chain link, to which the aforesaid link is applied, from being displaced transversely or rotated with the bending means. 105

6. A machine of the character described comprising means for advancing a chain, a guide through which the chain is advanced, means for bending a cross tie link around a link of the chain beyond said guide, and a support for the chain link beyond said bending means, said support having opposite abutments to hold the chain link between them against transverse displacement, one of the abutments being undercut to prevent the chain link from turning with said bending means, and said support having an inclined surface for the movement of the cross tie link over the corresponding abutment. 115 120 125

In testimony whereof I hereunto affix my signature.

GARY B. SMITH.
